CLAIM

The ornamental design for a combined orthopedic pillow and strapping, as shown and described.

DESCRIPTION

FIG. 1 is a prospective view of a combined orthopedic pillow and strapping, showing my new design;
FIG. 2 is a top plan view thereof;
FIG. 3 is a bottom plan view thereof;
FIG. 4 is a front elevational view thereof;
FIG. 5 is a back elevational view thereof;
FIG. 6 is a side elevational view thereof;
FIG. 7 is a side elevational view thereof, opposite that shown in FIG. 6; and,
FIG. 8 is a side elevational view thereof, in use position, the broken line showing of the legs is for illustrative purposes only and forms no part of the claimed design.
